ATTACHABLE ADVERTISING DEVICE

George S. Nelson, Revere, Mass., assignor to The
Forbes Lithograph Manufacturing Company,
Boston, Mass., a corporation of Massachusetts

Application April 9, 1941, Serial No. 387,627

5 Claims. (Cl. 40—25)

The invention relates to an improvement in attachable advertising devices in which the device is made attachable to any suitable support by means of sharp protruding pins or brads which penetrate the support for holding the device in place.

The object of the invention is to provide a new mode of applying the pins to the device, and holding them securely in place, which will require as few auxiliary parts as possible, and will admit of easy and simple assemblage. For securing this objective result the element or part carrying the pins is made the principal element for securing the pins in place, thus requiring little auxiliary assistance, and this by a mode of attainment which can best be seen and understood by reference to the drawing, in which—

Fig. 1 is a plan in unfolded extension of the element or part to which the pins are attached.

Fig. 2 is a side elevation of the folded element with the pins attached and in place.

Fig. 3 is a fragmentary plan of the structure shown in Fig. 2.

Fig. 4 is the same as Fig. 2 excepting that it shows the use of a different type of attached pin.

Fig. 5 is a view in front elevation of the complete pin attachable device shown supporting a swinging sign which is hung thereon.

Fig. 6 is a side elevation of the device slightly modified in structure and to which special reference will hereinafter be made.

Referring to the drawing: 1 represents a base sheet of any sort of foldable material. 2 are pins, or brads, carried by the sheet by which it is rendered attachable to a support. The pins are each provided with a head 3.

That portion of the sheet carrying the pins is provided with folds 4 and 5. Of these the fold 4 has jointed connection with the body of the sheet along a fold line 6 from which the fold 4 turns back over the face or side of the sheet. The fold 5 has jointed connection with the fold 4 along a fold line 7 from which the fold 5 turns forward to lie between the fold 4 and the side or face of the sheet over which the fold 4 is extending.

Thus there is provided a housing 8 within which those portions of the pins not protruding are contained. The pins are passed through the joint, formed by the fold line 6, between the body of the sheet and the fold 4 to leave protruding end portions 2'. The remaining body portions of the pins and attached heads are then socketed to lie parallel with each other within the housing 8, with the heads 3 of the pins contained between the folds 4 and 5, with bearing at the end of the

housing against the joint, formed by the fold line 7, between the two folds.

The two folds with the pins thus contained are then brought down into contact with the body of the base sheet over which the folds are extending to lie substantially parallel therewith. The folds and pins are then secured by wire staples 9, there being provided one staple for each pin. Each of these staples is passed through the respective folds and the base sheet and clinched, thus holding the folds and pins securely in place. Each staple embraces its accompanying pin so as to prevent lateral displacement of the pin. The staples are also located at points just forward of the heads of the pins so as to prevent longitudinal displacement of the pins in a forward direction; the displacement of the pins in the opposite or backward direction being prevented by the joint formed by the fold line 7 between the folds 4 and 5, against which the heads of the pins have bearing.

The base sheet 1 and attached pins may be used in any way as may be desired. In the drawing the base sheet is shown as providing a head-board or panel from which is hingedly hung, through interposed connecting clips 10, a swinging sign 11, which is simply illustrative of one way in which the attachable device may be used.

The base sheet is preferably provided with more than one pin, although in some cases a single pin may be all that is needed. Where a set of pins is required, instead of individual pins a U-shaped pin 12 may be employed, as shown in Fig. 4, its connecting bar 13 forming a head.

The base sheet, foldable to provide a housing within which the pin, or pins, are contained, may comprise a relatively small sheet, and this be reinforced and extended by an attached relatively stiff unfoldable sheet—the two combining to form a two-piece base sheet. Such a construction is shown in Fig. 6 where the base sheet 1, and its foldable pin carrying parts, is attached to a sheet 1a which may be a sheet of relatively stiff, unfoldable material. The attachment may be by the same staples 9, previously described, which, instead of being clinched beneath the base sheet 1, are extended through and clinched beneath the sheet 1a to which the sheet 1 is attached, and which co-operates therewith to form a combination base sheet.

I claim:

1. An attachable advertising device carrying a protruding pin by which it is made attachable to a support, and comprising a base sheet having a part foldable to provide a housing with

joints between its folds at the opposite ends of said housing, a pin contained within said housing with penetration through one of said joints to protrude therefrom and with head bearing against the other of said joints, and means binding together said assemblage of pin, folds, and base sheet and embracing said pin at a point forward of the head thereof.

2. An attachable advertising device carrying a protruding pin by which it is made attachable to a support, and comprising a base sheet with fold having jointed connection with said sheet along a fold line between it and said sheet, a pin contained between said fold and the adjacent body of said sheet with penetration through said joint and protruding therefrom, means binding together said assemblage of fold, pin, and base sheet and embracing said pin at a point forward of the head thereof whereby said pin will be held against longitudinal displacement in a forward direction, and means against which the head of said pin has bearing whereby it will be held against longitudinal displacement in a backward direction.

3. An attachable advertising device carrying a protruding pin by which it is made attachable to a support, and comprising a base sheet with folds, one a proximal fold having jointed connection with said base sheet along a fold line between it and said base sheet, the other of said folds having jointed connection with said proximal fold along a fold line between it and said proximal fold, a pin protruding from said folded sheet with head located between said folds and bearing against the joint between said folds, and

means binding together said assemblage of pin, folds, and base sheet and embracing said pin at a point forward of the head thereof.

4. An attachable advertising device carrying a protruding pin by which it is made attachable to a support, and comprising a base sheet with folds, the proximal one of said folds having jointed connection with said base sheet along a fold line between it and said base sheet, the other of said folds having jointed connection with said proximal fold along a fold line between it and said proximal fold, said folds combining to form a housing, a pin contained within said housing with penetration through the forward one of said joints to protrude therefrom and with head bearing against the hinder of said joints, and means binding together said assemblage of pin, folds, and base sheet and embracing said pin at a point forward of the head thereof.

5. An attachable advertising device carrying a protruding pin by which it is made attachable to a support, and comprising a base sheet including a relatively unfoldable part and a foldable part, said foldable part of the base sheet being foldable to provide a housing with joints between its folds at the opposite ends of said housing, a pin contained within said housing with penetration through the foremost one of said joints to protrude therefrom and with head bearing against the hinder one of said joints, and means binding together said assemblage of pin, folds and base sheet and embracing said pin at a point forward of the head thereof.

GEORGE S. NELSON.
